Dec. 1283

Garrison Smith & Henry Brown, of Philadelphia, Pa.

Assignors to
Abbott and Noble, of same place,
Letters Patent No 1283. Dated July 3, 1860.

The schedule referred to in these Letters Patent and making part of the same.

To all whom it may concern:

Be it known that we, Garrison Smith and Henry Brown, both
of the City of Philadelphia, State of Pennsylvania, have invented or produced a new and origi-
nal design for plates of a cooking stove termed the "Challenge", and we do hereby declare the
accompanying drawing and following explanation of the same to form a full clear and exact rep-
resentation and description of the said design.

Fig. 1, in the drawing represents the back plate.

Fig. 2, the upper front plate.

Fig. 3, the small door of the side plate.

Fig. 4, one of the oven doors.

Fig. 5, the lower front plate.

The back plate Fig. 1, and upper and lower front plates Figs.
2 and 5, are edged on the opposite ends with mouldings having oval projections, and at the top

and bottom with plain mouldings, the doors Figs. 3 and 4 as well as the doors connected to the front plate Fig. 5 having on the edges plain mouldings inclosing foliated and scroll ornaments of a character similar to that of the ornaments on the plates Figs. 1 and 2.

We claim the ornamental figures and forms represented in and by the accompanying drawing the whole forming an ornamental design for plates of a cooking stove.

Testimony whereof we have signed our names to this specification, in the presence of two subscribing witnesses.

Witnesses.
